CLAIM

The ornamental design for a truck rack panel, as shown and described.

DESCRIPTION

FIG. 1 is a front, bottom, and left-side perspective view of a first embodiment of a truck rack panel showing the new design;

FIG. 2 is a rear, top, and right-side perspective view thereof; FIG. 3 is a front elevation view thereof;

FIG. 4 is a rear elevation view thereof;

FIG. 5 is a right elevation view thereof;

FIG. 6 is a left elevation view thereof;

FIG. 7 is a top plan view thereof;

FIG. 8 is a bottom plan view thereof; and

FIG. 9 is a front, bottom, and left-side perspective view thereof, where the truck rack panel is in use on a truck rack. FIG. 10 is a front, bottom, and left-side perspective view of a second embodiment of a truck rack panel showing the new design;

FIG. 11 is a rear, top, and right-side perspective view thereof;

FIG. 12 is a front elevation view thereof;

FIG. 13 is a rear elevation view thereof;

FIG. 14 is a right elevation view thereof;

FIG. 15 is a left elevation view thereof;

FIG. 16 is a top plan view thereof;

FIG. 17 is a bottom plan view thereof; and,

FIG. 18 is a front, bottom, and left-side perspective view thereof, where the truck rack panel is in use on a truck rack. The dashed lines and structure they depict form no part of the claimed design.

1 Claim, 14 Drawing Sheets
